UNITED STATES PATENT OFFICE.

FRED WEGNER, OF FAIRPORT, NEW YORK, ASSIGNOR TO SANITARY CAN COMPANY,
OF NEW YORK, N. Y., A CORPORATION.

DOUBLE-SEAMING MACHINE.

1,104,751.

Specification of Letters Patent. Patented July 21, 1914.

Application filed September 27, 1909. Serial No. 519,794.

To all whom it may concern:

Be it known that I, FRED WEGNER, a citizen of the United States, residing in Fairport, in the county of Monroe and State of New York, have invented a new and useful Improvement in Double-Seaming Machines, of which the following is a specification.

My invention relates to improvements in double seaming machines.

10. The object of my invention is to provide a continuous, rotary double seaming machine of a simple, efficient and durable construction, which will be automatic in operation and of high capacity, enabling the heads or covers to be seamed on the bodies of cans very rapidly and cheaply, and in which at the same time the motion of the moving parts will be relatively slow and easy, which will operate to produce uniformly perfect 20 and hermetically tight double seams. The machine embodying my invention by which I practically accomplish this object or result, comprises in co-operative combination, a large, stationary, circular or convexly curved 25 seaming tool having a plurality of separate and individually adjustable seam forming segments, and a plurality of separate and individually adjustable seam closing segments, a can carrier having a plurality of 30 pairs of upper and lower rotary can holders or chucks thereon, the spindle of one can holder chuck of each pair having a gear meshing with a stationary gear for rotating the cans in the can holders as they are conveyed around by the carrier and thus rotated in contact with the stationary seaming tool, one of the can holders or chucks of 35 each pair being vertically movable to clamp and unclamp the cans, a feed device for automatically feeding or delivering the can 40 heads or covers upon the can bodies, and a feed device for automatically feeding or delivering the can bodies with the heads or covers thereon onto the lower can holders or chucks of the carrier as the carrier rotates continuously.

My invention also consists in the novel construction of parts and devices and in the novel combination of parts and devices herein shown and described and more particularly specified in the claims.

In the accompanying drawing forming a part of this specification, Figure 1 is a plan

view of a double seaming machine embodying my invention, a portion of the can body 55 conveyer being broken away. Fig. 2 is a front elevation. Fig. 3 is a detail horizontal section on line 3—3 of Fig. 2. Fig. 4 is a detail horizontal section on line 4—4 of Fig. 2. Fig. 5 is a detail side elevation showing 60 the can body feeder or placer. Fig. 6 is a horizontal section on line 6—6 of Fig. 2. Fig. 7 is a detail sectional view of the can head or cover feed device. Fig. 8 is a detail section of the seaming tool through one of 65 the seam forming segments. Fig. 9 is a detail section through one of the seam closing segments.

In the drawing, A represents the frame of the machine; B is the stationary seaming 70 tool; C is the stationary gear for rotating the can holders; D D¹, upper and lower rotary can holders or chucks, E the continuously rotating carrier upon which the rotary can holders are mounted, F the can body 75 feeder or placer for feeding or delivering the cans one by one onto the lower chucks or holders of the carrier, G a can conveyer and H a can head or cover feeder for feeding or delivering the can heads or covers one by 80 one onto the can bodies.

The frame A may be of any suitable kind or construction adapted to give support or mounting to the other parts or devices of 85 the machine.

The large, stationary, convexly curved or circular seaming tool B, preferably comprises a series or plurality of separate and independently adjustable seam forming segments b, preferably six in number, and a series or plurality of separate and independently adjustable seam closing segments b¹, adjustably secured to a ring B¹ by set screws b² and adjusting screws b³ so that each successive tool segment b b or b¹ b¹ may be set 95 or adjusted slightly radially outward in respect to each preceding segment to cause the seam to be progressively formed and progressively closed as the can is conveyed and 100 axially rotated around and in rolling contact with the seaming tool. All the seam forming segments b preferably have the same contour of seaming groove, and all the seam closing segments b¹ likewise preferably have the same seam closing groove or contour for engagement with the seam flanges 105.

of the can body and can head or cover or the seam formed by the interlocking or curling of same.

5 The stationary gear C by which the rotary can holders are rotated as they are conveyed around the circular or convexly curved seaming tool is preferably an ordinary spur gear and may be formed of a separate piece, or integral with the ring B¹ or with a portion 10 of the frame, as may be preferred.

The can carrier E has an upright shaft or spindle E¹ journaled in the frame of the machine, and is continuously rotated from the driving shaft N, through suitable gearing; the same preferably comprising a spur gear n on the driving shaft N meshing with a spur gear m¹ on the countershaft M, having a bevel gear m meshing with a bevel gear E² on a sleeve E⁵ having a spur gear E⁶ meshing 15 with a spur gear E⁷ on shaft E⁸, said gear E⁷ also meshing with a gear E⁹ on the upright shaft E¹⁰ which bears at its upper end a spur gear E¹¹ which meshes with the internal gear E¹² on the lower portion or spider of 20 the carrier E. The can carrier is preferably furnished with six can holder yokes E³ upon which the upper and lower rotary can holders or chucks D D¹ are mounted, the can holder yokes being adjustably secured 25 to the can carrier by set screws E⁴.

The spindle d of each of the upper rotary can holders or chucks D is furnished with a spur gear d¹ meshing with a stationary gear C to cause the can holder chuck to be 30 axially rotated as the carrier E travels around the stationary gear. The spindle d² of each of the lower can holders or chucks D¹ may also be preferably positively driven or rotated, and this is preferably done 35 through an intermediate shaft d¹² journaled on each of the yokes E³, and having a gear d³ meshing with the gear d¹¹ on the spindle of the upper chuck or holder D, and provided with a further gear d⁴ meshing with 40 a gear d⁵ on the spindle d² on the lower chuck or holder D¹. The upper and lower can holders or chucks D D¹ of each pair are thus caused to be positively driven or rotated in unison with each other. The lower 45 can holders or chucks D¹ are preferably the ones which are made vertically movable to clamp and unclamp the cans between the upper and lower chucks. The spindle d² of the lower chuck D¹ preferably has a splined connection d⁶ with its gear d⁵ to permit of the raising and lowering movement of the lower chuck. The lower chuck or can holder D¹ is preferably moved up and down as required to clamp and unclamp the can 50 and held or maintained in its raised or clamping position during the seaming operation by means of a stationary track or cam O on the frame of the machine, which is engaged by a roller d⁷ on a slide d⁸, the upper end of which engages the lower end 55

of the chuck spindle d². The high portion o¹ of the stationary cam or track O holds or maintains the lower chuck D¹ in its raised position as it is conveyed around by the carrier E.

70 The can bodies X with the can heads or covers X¹ thereon ready to be seamed there-to are automatically fed or delivered one by one onto the lower can holder or chuck D¹ of the carrier E by means of a can feeder 75 or placer F which operates to push the can from the feed table P onto the holder as the holder moves into registry or co-operative relation with the can feeder or placer F. The can feeder or placer F preferably has a 80 reciprocatory movement horizontally and radially toward the center of the carrier E. The can feeder or placer F is preferably furnished with a pair of outer can head centering pins f, which, by engagement with 85 the seaming flange x of the can head or cover X¹ serve to center the can head with the can body in conjunction with an inner pair of can head centering pins f¹ which are 90 preferably mounted movably on the yoke E³ of the carrier E so that this inner pair of can head centering pins f¹ may be moved or rocked slightly out of the way after the can has been placed on the lower chuck D¹ by the feeder or placer F and before the 95 lower chuck D¹ moves upward to clamp the can between itself and the upper chuck or holder D. The can feeder or placer F has a stem or slide f² and is preferably operated by a cam f³ on the shaft f⁴ driven by 100 the main shaft through a lever f⁵, a spring f⁶ being provided to return the can feeder or placer F to position.

The inner or movable pair of can head centering pins f¹ are preferably rocked or 105 moved out of the way by means of a bent lever f⁷, the lower arm f⁸ of which is engaged by a spring secured to the yoke E³.

The can bodies with the can heads or covers in place thereon are preferably conveyed or moved along the feed table P into position in front of the reciprocating can head feeder or placer F by means of a can conveyer G, having fingers g adapted to engage the cans. The conveyer G preferably 110 consists of an endless belt or chain mounted upon a pulley G¹. The feed table P is preferably furnished with side guides P¹. The can heads or covers X¹ are preferably fed or delivered one by one to each can body X 115 from the can head or cover holder S by a movable feeder H, having upper and lower fingers or blades h h¹ adapted to release the lowermost can head or cover from the pile or stack at each movement of the feeder. The feeder is preferably intermittently operated as required by cam links h² connected to the arms of a pair of rock shafts h³ which have further arms h⁴ connected to the operating rod or link h⁴. As the cam links h² 120 125 130

are moved up and down they alternately engage and operate the two feeder blades h h^1 , thus causing the upper one to support the stack or pile of can heads while the lower 5 blade withdraws to release the lowermost can head.

The large convexly curved seaming tool B is preferably sufficiently large in diameter to cause each can to make at least ten complete 10 axial rotations or six revolutions in contact with the seam forming portion of the tool and four revolutions in contact with the seam closing portion of the tool. The large diameter of the seaming tool B in respect to 15 the diameter or size of the can gives an increased line of contact of the tool with the can flanges or seam during the seaming operation, and thus serves to insure perfection and tightness of the seam as compared with 20 the result secured by the ordinary rotary small diameter seaming roller or tool commonly used in double seaming machines. The seam forming segments b of the stationary seaming tool B preferably have sub- 25 stantially the same contour of double seaming groove as that ordinarily employed in double seaming machines for the rotary small diameter seaming rollers. And the same is true of the seam closing segments b^1 30 of my seaming tool B.

As the rotary can carrier E has a large or any desired number of axially rotatable can holders thereon, and as it may move at a relatively slow speed, while the machine 35 as a whole has a high capacity, the reciprocating can feeder or placer F may be readily operated to feed or place the cans accurately and properly upon each lower can holder or chuck D¹ as the same comes into can receiving 40 position while the carrier E is under continuous motion. By adjusting the can holders D D¹ radially in and out on the carrier E, the machine is adapted to operate on cans of different diameters. The can 45 holders D D¹ may be adjusted an amount equal substantially to the sum of the depth of the teeth on the intermeshing gear and pinions C and d^1 and the amount of adjustment allowed by the sectional seaming 50 tool B.

I claim:

1. In a double seaming machine, the combination with a series of axially rotatable can holders, of a rotary carrier upon which 55 they are mounted, and a stationary convexly curved seaming tool, said seaming tool being convexly curved in the direction of its length and being on the inner side of the path of the can holders, and having a plurality of separate and independently adjustable seam forming segments, substantially as specified.

2. In a double seaming machine, the combination with a series of axially rotatable 60 can holders, of a rotary carrier upon which

they are mounted, and a stationary convexly curved seaming tool, said seaming tool being convexly curved in the direction of its length and being on the inner side of the path of the can holders and having a plurality of separate and independently adjustable seam forming segments, and a plurality of separate and independently adjustable seam closing segments, substantially as specified. 70 75

3. In a double seaming machine, the combination with a series of radially adjustable axially rotatable can holders, of a rotary carrier upon which they are mounted, a stationary convexly curved seaming tool, and a stationary cam for operating the can holders to clamp and unclamp the cans, a can conveyer, a can head holder and feeder above said conveyer for delivering the can heads to the cans and a feeder for delivering the cans to said can holders, substantially as specified. 80 85

4. In a double seaming machine, the combination with a series of axially rotatable can holders, of a rotary carrier upon which they are mounted, a stationary convexly curved seaming tool having separately adjustable seam forming and closing segments, a can feeder and can head centering pins, substantially as specified. 90 95

5. In a double seaming machine, the combination with a series of axially rotatable can holders, of a rotary carrier upon which they are mounted, a stationary convexly curved seaming tool, a can feeder having an outer pair of can head centering pins, and an inner movable pair of can head centering pins, substantially as specified. 100

6. In a double seaming machine, the combination with a rotating carrier having a series of pairs of upper and lower can holding chucks, of a stationary gear for driving one chuck of each pair, and connecting gearing for driving the other chuck of each pair from the driven chuck thereon, a stationary convexly curved seaming tool having separately adjustable seam forming and seam closing segments inside the path of said holders, substantially as specified. 110 105

7. In a double seaming machine, the combination with a rotating carrier having a series of pairs of upper and lower can holding chucks, of a stationary gear for driving one chuck of each pair, connecting gearing for driving the other chuck of each pair 120 from the driven chuck thereof, and a stationary seaming tool convexly curved in the direction of its length and having seam forming and seam closing segments and means for adjusting said segments independently of each other, substantially as specified. 125

8. In a double seaming machine, the combination with a rotating carrier having a series of pairs of upper and lower can hold- 130

ing chucks, of a stationary gear for driving one chuck of each pair, connecting gearing for driving the other chuck of each pair from the driven chuck thereof, and a stationary seaming tool convexly curved in the direction of its length and having seam forming and seam closing segments and means for adjusting said segments independently of each other, one chuck of each pair being adapted to reciprocate to and from the other, and a stationary cam or track for operating the reciprocating chuck of each pair, substantially as specified.

9. In a double seaming machine, the combination with a convexly curved stationary seaming tool having a plurality of separate and independently adjustable seam forming segments and a plurality of separate and independently adjustable seam closing segments, of means for conveying and rotating cans around and in contact with said seaming tool, said tool being convexly curved in the direction of its length and being on the inner side of the path of the cans, substantially as specified.

10. In a double seaming machine, the combination with a convexly curved stationary seaming tool having a plurality of separate and independently adjustable seam forming segments and a plurality of separate and independently adjustable seam closing segments, of means for conveying and rotating cans around and in contact with said seaming tool, said tool being convexly curved in the direction of its length and being on the inner side of the path of the cans in said can holder chucks, substantially as specified.

11. In a double seaming machine, the combination with a convexly curved stationary seaming tool having a plurality of separate and independently adjustable seam forming segments and a plurality of separate and independently adjustable seam closing segments, of means for conveying and rotating cans around and in contact with said seaming tool, said can conveying and rotating means comprising a carrier furnished with a series of opening and closing rotatable can holder chucks, and a can feeder, substantially as specified.

55 12. In a double seaming machine, the combination with a convexly curved stationary seaming tool having a plurality of separate and independently adjustable seam forming segments and a plurality of separate and independently adjustable seam closing segments, of means for conveying and rotating cans around and in contact with said seaming tool, said can conveying and rotating means comprising a carrier furnished with a series of opening and closing rotatable can

holder chucks, a can feeder, and a can conveyor, substantially as specified.

13. In a double seaming machine, the combination with a convexly curved stationary seaming tool having a plurality of separate and independently adjustable seam forming segments and a plurality of separate and independently adjustable seam closing segments, of means for conveying and rotating cans around and in contact with said seaming tool, said can conveying and rotating means comprising a carrier furnished with a series of opening and closing rotatable can holder chucks, a can feeder, a can conveyor, and a can head feeder, substantially as specified.

14. In a double seaming machine, the combination with a stationary, convexly curved, seaming tool having separate piece seam-forming and seam-closing segments, of a stationary gear concentric therewith, a continuously rotating can carrier having a series of upper and lower, simultaneously radially adjustable, axially rotatable can holder chucks, and gears on said chucks meshing with said stationary gear to rotate the cans with their seam flange in contact with said stationary, convexly curved, seaming tool, said tool being convexly curved in the direction of its length and being on the inner side of the paths of the can holders, substantially as specified.

15. In a double seaming machine, the combination with a series of radially, adjustable, axially rotatable can holders, of a rotary can carrier upon which they are mounted, a stationary, convexly curved, seaming tool, a stationary gear for axially rotating each of said can holders as they are conveyed around by said carrier and a feeder for delivering cans to said can holders, each of said upper and lower chucks being positively rotated, substantially as specified.

16. In a double seaming machine, the combination with a series of axially rotatable can holders, of a rotary can carrier upon which they are mounted, a stationary, convexly curved, seaming tool having separate, adjustable, seam-forming and seam-closing segments, and a stationary gear for axially rotating said can holders as they are conveyed around by said carrier, each of said can holders having a spindle furnished with a gear meshing with said stationary gear, substantially as specified.

17. In a double seaming machine, the combination with a series of axially, rotatable can holders, of a rotary can carrier upon which they are mounted, a stationary, convexly curved, seaming tool, a stationary gear for axially rotating said can holders as they are conveyed around by said carrier, said can holders having spindles furnished with gears meshing with said stationary gear, said carrier being provided with pivotally

- mounted, can head centering means at each set of can holders, and a stationary cam for operating the can holders to clamp and un-clamp the cans, substantially as specified.
5. 18. In a double seaming machine, the combination with a rotary carrier, of a plurality of sets of axially rotatable can holders, each set comprising an upper and a lower clamping member, a stationary convexly curved 10 seaming tool having separate seam-forming and seam-closing segments, and mechanism for positively rotating each of the members of each set of can holders, substantially as specified.
15. 19. In a double seaming machine, the combination with a series of axially rotatable can holders, of a rotary carrier upon which they are mounted, a stationary, convexly curved, seaming tool, the same being comprised of a plurality of separate piece seam-forming and seam-closing segments, a can 20 feeder for delivering the cans one by one to said can holders, a can feed table, a can conveyer, and pivotally mounted can head centering means on said carrier, substantially as specified.
20. In a double seaming machine, the combination with a rotary carrier, of a plurality of radially adjustable yokes E^3 mounted on 30 said carrier, each yoke having rotatably mounted therein an upper and lower can holding chuck, whereby the upper and lower chucks in each yoke may be simultaneously inwardly and outwardly adjusted relatively 35 to the axis of rotation of the carrier, and a stationary seaming tool convexly curved in the direction of its length, substantially as specified.
40. 21. A double seaming machine including, in combination: a seaming tool convexly curved in the direction of its length; a rotatable carrier; a pair of alined, axially rotatable can holders; and means in which said holders are mounted, said means being
- carried by and adjustable on said carrier 45 whereby said holders may be simultaneously adjusted in and out relatively to the seaming tool, substantially as specified.
22. A double seaming machine including, in combination: a seaming tool convexly 50 curved in the direction of its length, said seaming tool having separate seam-forming and seam-closing segments; a rotatable carrier; a set of axially rotatable can holders carried by said carrier, said set comprising 55 an upper and a lower clamping member; and mechanism for positively rotating both of said can holders, substantially as specified.
23. A seaming machine including, in combination: a seaming tool convexly curved in 60 the direction of its length; a rotatable carrier; a pair of alined, axially rotatable can holders; a yoke in which said holders are rotatably mounted, said yoke being substantially radially adjustably mounted on said 65 carrier, whereby said holders may be simultaneously inwardly and outwardly adjusted relatively to the axis of rotation of the carrier; and mechanism for positively rotating both of said holders, substantially as speci- 70 fied.
24. A seaming machine including, in combination: a seaming tool convexly curved in the direction of its length; a rotatable carrier; a pair of alined, axially rotatable can 75 holders; a yoke in which said holders are rotatably mounted, said yoke being substantially radially adjustably mounted on said carrier, whereby said holders may be simultaneously inwardly and outwardly adjusted 80 relatively to the axis of rotation of the carrier; and mechanism for positively rotating one of said holders, substantially as speci- fied.

FRED WEGNER.
